LATHING

Carl A. Karelus, Pasadena, Calif.

Application January 25, 1938, Serial No. 186,831

8 Claims. (Cl. 72—116)

This invention relates generally to building construction and more particularly to lathing which provides a foundation for plaster or other cementitious material used in forming walls and 5 ceilings.

An object of the invention is to provide lathing of the wire and backing sheet type which is structurally characterized in a manner to enable the second coat of plaster to be applied immediately 10 after the first coat without displacing the latter or affecting its bond with the backing sheet and wire, whereby to effect a saving in labor and to avoid parting of one coat from another as a result 15 of inefficient bonding of the second coat to the first coat when the latter is permitted to set for a day or more, as is the present practice.

Another object of the invention is to provide lathing wherein the backing sheet and reinforcing wires are correlated to prevent excessive flexing 20 of the backing sheet and to insure substantially unitary movement of the latter and the wires when applying the plaster, so as to obviate breaking of the temporary suction bond between the plastic mass and the backing sheet, as well 25 as loosening of the mass from the wires by pressure of the trowel during working of the wet plaster coat.

Another object of the invention is to provide lathing which enables a plaster coat of uniform 30 thickness to be obtained so as to produce a wall of maximum strength with a minimum amount of plaster.

A further object of the invention is to provide wire reinforced lathing which can be cut or 35 trimmed to any size required and yet retain support for the back sheet by wires at both sides thereof to its edges, and which enables lapped selavage edges of adjacent sections of the lathing to be anchored together by the plaster to obtain 40 the effect of a continuous lath foundation throughout the entire area of a wall or ceiling.

With these and other objects in view, the invention consists of the following combinations and arrangements of elements as set forth in 45 the following specification and particularly pointed out in the appended claims.

In the accompanying drawings,

Figure 1 is a view in front elevation of the lathing embodying this invention, as applied to 50 joists or studs;

Figure 2 is a view of the lathing in rear elevation;

Figure 3 is a horizontal sectional view taken on 55 the line 3—3 of Figure 1;

Figure 4 is a view in rear elevation showing the lathing with plaster applied thereto;

Figure 5, 6, 7 and 8 are enlarged fragmentary sectional views taken, respectively, on the lines 5—5, 6—6, 7—7 and 8—8 of Figure 4.

Referring specifically to the drawings, the invention in its present embodiment comprises a backing sheet 10 of building paper, cardboard or other similar material having openings 11 therethrough, arranged in longitudinal and transverse 10 rows. These openings are illustrated as being square in outline and are disposed obliquely with respect to the directions of the rows as clearly shown in Figures 1 and 2.

At the rear of the backing sheet are stiffener 15 members 12 in the form of metal bars of substantially V shape in cross section, which are disposed to span alternate rows of the openings 11. Arranged intermediate and in parallelism with the members 12 are rear wires 13 which span 20 alternate rows of the openings 11. Other rear wires 14 are disposed at a right angle to the members 12 and wires 13 so as to be in intersecting relation thereto, and to span alternate rows of the openings 11, all as clearly shown in Figures 1 25 and 2.

The wires 14 are electrically welded or otherwise permanently secured to the wires 13 and members 12 at their points of intersection therewith, and are woven in and out of the wires 13 30 and members 12 so as to be disposed at the rear of the wires 13 and at the front of the members 12.

At the front of the backing sheet are wires 35 15 arranged intermediate and in parallelism with the wires 14 so as to span alternate rows of the openings 11. The front wires 15 are electrically welded or otherwise permanently secured to the members 12 and rear wires 13 at their points of intersection therewith. Other front wires 16 are 40 disposed midway between and in parallelism with the members 12 and rear wires 13, and are electrically welded to the first mentioned front wires 15 at their points of intersection therewith, as clearly shown in Figure 1.

Sheets of the lathing as above described are nailed or stapled to joists or studs A at the stiffener members 12 as indicated at 17 in Figure 1, so that the edges of adjacent sheets overlap approximately the distance between the wires 14 45 and 15 in order to provide for maximum keying of the sheets together when plaster is applied thereto.

When the sheets of lathing are thus in place, a coat of plaster is applied thereto, portions of the 50 55

plaster being forced through the openings 11 around the stiffener members 12 and around the wires 13, 14 and 15 at their points of intersection in the respective openings, so as to form 5 protuberances or keys K in the openings. Plaster is also forced between the front wires 15, 16 and the backing sheet 10 to form additional keys K' and K² shown in Figures 5 and 6, respectively.

A second coat of plaster is immediately applied 10 to the first coat and will not dislodge the latter from the wires and the backing sheet, due to the fact that the front and rear wires co-act to compel movement of the lathing resulting from pressure of the trowel, to take place generally as a 15 unitary movement of the entire lathing structure rather than one in which excessive flexing of the backing sheet relative to the wires is effected and causes the temporary suction bond between the softened backing sheet and first wet coat of 20 plaster to be broken.

Furthermore, the keys K, in addition to locking the plaster to the members 12 and to the front and rear wires 13, 14 and 15, prevent shifting of the 25 plastic mass parallel to the plane of the lathing as the mass is being worked with a trowel, thus further insuring that the first wet coat of plaster will not become dislodged from the lathing. It will be noted that the keys K are also formed at the lap joints between sheets of the 30 lathing so that the latter are locked together to have the effect of a continuous sheet over the entire area of a wall.

It will be appreciated that should any of the 35 welded connections between the wires and between the members 12 and the wires become broken, that the keys K will adequately support the plaster slab, and that the stiffener members 12, in addition to their reinforcing function, provide maximum anchorage for the plaster slab 40 through the medium of the keys, as well as take the place of wires.

As a result of minimum flexing of the backing sheet, a more uniform thickness of plaster can be maintained throughout the area of the slab so as 45 to obtain maximum strength with a minimum quantity of plaster. By the elimination of all lateral offsets in the wires employed, the stretching of the wires is overcome, and cracking of plaster from this source prevented.

Irrespective of the location at which a sheet of 50 the lathing may be trimmed longitudinally or transversely, the front and rear wires will support the backing sheet 10 to its edges, and the trimming operation can be effected at such points that 55 the wires 13, 16 or 14, 15 will provide a selvage edge with the backing sheet securely held against lateral displacement, all as clearly shown in Figure 1.

It has been found in practice that by the use 60 of the lathing embodying this invention two coats of plaster can be successfully applied, one immediately after the other, so as to obtain the advantage of a perfect physical bond between two wet coats, and to eliminate the delay and added labor 65 otherwise necessary to later apply the second coat.

What is claimed is:

1. Lathing comprising a backing sheet having 70 openings therein; stiffener members arranged in spaced parallelism at one side of said sheet and spanning said openings; rear wires arranged intermediate and parallel to said members at said one side of said sheet, and spanning others of said openings; other rear wires intersecting and secured to said members and first said rear wires 75 at said openings; and means co-acting with the

stiffener members and wires to secure them against displacement from the backing sheet.

2. Lathing comprising a backing sheet having 5 openings therein; stiffener members arranged in spaced parallelism at one side of said sheet and spanning said openings; rear wires arranged intermediate and parallel to said members at said one side of said sheet, and spanning others of said openings; other rear wires intersecting and secured to said members and first said rear wires at 10 said openings; and front wires at the other side of said sheet, intersecting and secured to said members and first said rear wires at others of said openings, for co-action in securing the members and wires to the sheet. 15

3. Lathing comprising a backing sheet having 20 openings therein; stiffener members arranged in spaced parallelism at one side of said sheet and spanning said openings; rear wires arranged intermediate and parallel to said members at said 25 one side of said sheet and spanning others of said openings; other rear wires intersecting and secured to said members and first said rear wires at said openings; front wires at the other side of said sheet intersecting and secured to said members and first said rear wires at others of said 30 openings, for co-action in securing the members and wires to the sheet; and other front wires at said other side of the sheet, intersecting and secured to the first said front wires intermediate 35 the stiffener members and first said rear wires.

4. Lathing comprising a backing sheet having 40 openings therein; stiffener members arranged in spaced parallelism at one side of said sheet and spanning said openings; rear wires arranged intermediate and parallel to said members at said 45 one side of said sheet, and spanning others of said openings; other rear wires intersecting and secured to said members and first said rear wires at said openings; front wires at the other side of said sheet, intersecting and secured to said 50 members and first said rear wires at others of said openings, for co-action in securing the members and wires to the sheet; and other front wires at said other side of the sheet, intersecting and secured to the first said front wires intermediate 55 the stiffener members and first said rear wires, said front and rear wires co-acting in their intersecting relationship, to support the backing sheet laterally, and to provide a selvage edge along the longitudinal and transverse edges of the backing sheet.

5. Lathing comprising a backing sheet having 60 openings therein; stiffener members arranged in spaced parallelism at one side of said sheet and spanning said openings; rear wires arranged intermediate and parallel to said members at said 65 one side of said sheet, and spanning others of said openings; other rear wires intersecting and secured to said members and first said rear wires at said openings; front wires at the other side of said sheet, intersecting and secured to said members and first said rear wires at others of said 70 openings, for co-action in securing the members and wires to the sheet; said front and rear wires co-acting to support the backing sheet to its longitudinal and transverse edges irrespective of the size to which the lathing is trimmed. 75

6. Lathing comprising a backing sheet having 70 openings therein; stiffener members arranged in spaced parallelism at one side of said sheet and spanning said openings; rear wires arranged intermediate and parallel to said members at said 75 one side of said sheet, and spanning others of said openings; other rear wires intersecting and

secured to said members and first said rear wires at said openings; front wires at the other side of said sheet, intersecting and secured to said members and first said rear wires at others of said 5 openings, for co-acting in securing the members and wires to the sheet; and other front wires at said other side of the sheet, intersecting and secured to the first said front wires intermediate the stiffener members and first said rear wires, 10 said front and rear wires co-acting in their intersecting relationship, to support the backing sheet laterally, and to provide a selvage edge along the longitudinal and transverse edges of the backing sheet. 15

7. Lathing comprising a backing sheet having 20 openings therein; stiffener members arranged in spaced parallelism at one side of said sheet and spanning said openings; rear wires arranged intermediate and parallel to said members at said one side of said sheet, and spanning others of said 25 openings; front wires at the other side of said sheet, intersecting and secured to said members and said rear wires at others of said openings, for co-action in securing the members and wires to the sheet; and other front wires at said other 30 side of the sheet, intersecting and secured to the

first said front wires intermediate the stiffener members and said rear wires, said front and rear wires co-acting in their intersecting relationship, to support the backing sheet laterally, and to provide a selvage edge along the longitudinal and 5 transverse edges of the backing sheet.

8. Lathing comprising a backing sheet having 10 openings therein; stiffener members arranged in spaced parallelism at one side of said sheet and spanning said openings; rear wires arranged intermediate and parallel to said members at said one side of said sheet, and spanning others of said 15 openings; front wires at the other side of said sheet, intersecting and secured to said members and said rear wires at others of said openings, for coacting in securing the members and wires to the sheet; and other front wires at said other side of the sheet, intersecting and secured to the first said front wires intermediate the 20 stiffener members and said rear wires, said front and rear wires co-acting in their intersecting relationship, to support the backing sheet laterally, and to provide a selvage edge along the longitudinal and transverse edges of the backing sheet, 25 the selvage edge of one lathing adapted to overlap the selvage edge of another lathing to enable the adjacent lathings to be anchored together by plaster so as to have the effect of a continuous foundation.
